[57] CLAIM

The ornamental design for a cooler, as shown and described.

DESCRIPTION

FIG. 1 is a left side, top, perspective view of the cooler thereof;

FIG. 2 is a front side elevational view thereof;

FIG. 3 is a rear side elevational view thereof;

FIG. 4 is a left side elevational view thereof, a right side elevational view being a mirror image thereof;

FIG. 5 is a top plan view thereof; and,

FIG. 6 is a bottom plan view.

The broken lines are for illustrative purposes only and form no part of the claimed design.
